GEORGE J. MEUER AND ARTHUR H. FLEET, OF MILWAUKEE, WISCONSIN, ASSIGNEES,
BY MESNE ASSIGNMENTS, TO CUTLER-HAMMER, INC., A CORPORATION OF DELA-
WARE.

ELECTRIC SWITCH.

Application filed January 22, 1923. Serial No. 614,098.

This invention relates to electric switches and while not limited thereto is particularly applicable as a starting and control switch for single phase and other motors having 5 plural circuit connections requiring different commutation for starting and running respectively.

The present invention has among its objects that of providing a snap switch for 10 the foregoing and other purposes having combined therewith thermo-responsive means to act thereon for providing features of automatic control of the motor or the like.

Another and more specific object is that 15 of providing a peculiarly advantageous combination involving such a switch and thermo-responsive means.

Another object is that of providing an 20 improved thermo-responsive element for use in the foregoing and other relations.

Another object is that of providing improved snap switch mechanism adapted to control both of alternating and direct current and applicable with peculiar advantage 25 to control of the former.

Other objects and advantages will hereinafter appear.

In the accompanying drawing, wherein is 30 illustrated an embodiment of the invention,

Figure 1 is a plan view thereof, the housing being shown in section;

Fig. 2 is a side elevational view of the same;

Fig. 3 is a similar view but from a rectangularly displaced position; while

Figs. 4 and 5 are vertical sectional views upon lines 4-4 and 5-5 of Fig. 1 respectively.

Referring to the drawing the same illustrates a circular insulating base 9 for support of the hereinafter described parts, a snap switch mechanism carried by the base and biased to open position but provided with a latch for holding the same closed, thermostatically controlled means for tripping said latch and jointly operable auxiliary switching apparatus adapted in the illustrated structure to complete the circuit of the auxiliary starting winding of the motor or the like upon actuation of the closing means for the snap switch and further adapted to interrupt said circuit of the auxiliary starting winding automatically upon release of the snap switch closing mechanism.

Said base 9 is further provided with suitable openings for the necessary lead-in wires and is adapted to receive a substantially cylindrical housing 10 having openings through which the voluntarily controllable operating elements for the device are adapted to project.

More specifically the snap switch mechanism comprises a pair of similar fixed contacts 11 and 12 carried in spaced and insulated relation upon the base 9 and adapted to be bridged by an oscillatable contactor 13. The supporting and operating means for said contactor 13 may preferably comprise a rigid U-shaped metallic support 14 fixed upon the base 9 with its parallel portions 15 and 16 arranged substantially parallel to the upper or frontal plane of the base 9 and extending toward the switch fixed contacts. A U-shaped contact arm 17 is terminally pivotally mounted upon the central portion 75 of the support 14 for oscillation with respect thereto in substantially coplanar relation to the support 14. An operating member 18 having a suitably located push button or the like 19 is arranged to slide within a suitable slot of the support 14 and substantially at right angles to the portions 15 and 16 thereof. A tension spring 20 is terminally connected to the free end of the contact arm 17 and to an intermediate portion of the 80 operating member 18, whereby in extreme positions of said operating member the tension of said spring serves to hold the contact arm 17 in a corresponding extreme position and against one or the other of the 85 laterally projecting portions 15 and 16 of the support 14 whereas upon movement of the operating member from one extreme position to the other the fulcrum of the spring is shifted past the pivotal axis of said contact arm whereby the latter is drawn to its opposite extreme position with a snap action in a conventional manner. The contactor 13 is carried by and in insulated relation to the free end of the contactor arm 17 and 90 is adapted in its down position to bridge the fixed contacts 1 and 12 and in its up position to be relatively widely separated from both of said contacts whereby the controlled circuit is respectively completed and 95 interrupted.

A relatively heavy spring 21 is located within the base 9 and adapted to exert a

thrust upon the operating member 18 thereby serving to bias the switch to open position. A projecting lug 22 is provided upon the contact arm 17 to extend radially of the latter and preferably beyond the position of the contactor 13. A pivoted latch 23 is carried upon a suitable support 24 which latter is fixed to the base 9, said latch having a light tension spring 25 terminally connected to the support, and to said latch by means of an integral projecting lever 26 located beyond the pivot point of said latch, the function of said spring being that of biasing the latch into a position such as to engage the lug 22 of the contact arm for holding in the contactor.

Here it may be noted that the afore-described combination and arrangement of the restraining latch with the switch mechanism whereby the former acts directly upon the contacting element and moreover under exceedingly favorable conditions of mechanical advantage, enables mounting and adjustment of the latch member such as to enable release of the latch by a minimum expenditure of force operating through a minimum distance while nevertheless providing for exceedingly positive and reliable latching and holding action.

30 The thermo-responsive releasing means for said latch may preferably comprise a thermostatic element 27 of special construction to be hereinafter described, said element being preferably terminally anchored to and insulated from the lower end of the latch support 24 and adapted to extend substantially parallel with the upper portion of the latch 23. Said latch is provided with an adjustable screw 28 extending toward the upper end of said thermostatic element for actuation by the latter under given thermic conditions to thereby effect tripping of the latch against the tension of the spring 25 with consequent release of the switch contactor and opening of the switch under the tension of the spring 20.

50 The thermostatic element 27 preferably comprises a bimetallic or other suitable sheet or strip of reflexed or substantial grid formation as illustrated more clearly in Fig. 3, one terminal of the grid being riveted or otherwise mechanically and electrically connected with a suitable terminal 29 which may preferably comprise one of the connections to the motor or similar appliance to be controlled. The opposite terminal of the grid is similarly connected to a bus bar or jumper 30 which is in turn electrically connected with contact 12 of the snap switch whereby the thermostatic element is adapted to be traversed by the current passing through the motor or other controlled device.

60 The free end of thermostatic element 27 is provided with an insulated clip or binding element 27^a serving to insure against

independent or relative movement of the several convolutions of said thermostatic element.

The aforescribed grid formation of the thermostatic element serves to constitute the latter in effect an ohmic heating device whereby the use of an extraneous heating element for the thermostat is obviated. Again the aforescribed construction of the thermostatic element whereby a large number of plies of the latter are arranged in mechanically parallel relation serves to increase the mechanical force developed by said element under given thermic conditions, or more accurately to concentrate the developed force within a restricted range of movement, thereby peculiarly adapting the thermostatic element to co-operate with the latching mechanism aforescribed.

65 The fixed contacts 11 and 12 of the snap switch are also of special and improved construction as illustrated particularly in Fig. 5. Said contacts are in practice preferably formed to provide collectively spaced parallel surface portions to be directly engaged and bridged by the contactor 13 and with upwardly extending divergent surface portions 11^a and 12^a between which said contactor is adapted to travel substantially longitudinally.

70 This arrangement has been found in practice exceedingly desirable, particularly in control of alternating current inductive circuits, since during circuit interruption the contactor after movement out of actual engagement with the fixed contacts continues to travel in close but gradually lessening proximity to the adjacent divergent contact surfaces, whereby the length of any resultant arcs is increased only very slowly thus affording time for the current to pass through its zero value and thus become interrupted while the arc remains relatively short and weak.

75 The aforescribed coaction of the contactor and contacts provides, with either alternating or direct current, for closure of the circuit with a quick and positive snap action and also provides for presenting successively new and cold areas of the fixed contacts to the action of any arcs which may be drawn during interruption of circuit, thereby cooling and expediting extinguishment of such arcs and limiting the regions of possible burning of the fixed contacts to areas thereof which are not involved in the transmission of current while the switch is fully closed.

80 The snap switch contact 11 is connected by means of a suitable bus bar or the like to a terminal device 31 which in practice is preferably connected to the source of current supply.

85 Also where the switch is intended for the control of a single phase or other motor hav-

ing a starting winding or the like to be un-
energized during normal running, the ter-
minal device 31 is preferably extended
upwardly as shown particularly in Fig. 5,
5 whereas an additional contact and terminal
device 32 is riveted or otherwise secured to
such extension but insulated therefrom sub-
stantially as illustrated. A resilient con-
tactor 33 is further riveted or otherwise me-
chanically and electrically connected to the
10 terminal device 31 as shown more clearly
in Fig. 1, said contactor having a part to
engage the contact device 32 but being nor-
mally biased out of such engagement. The
15 contact is further provided with a portion
adapted to be engaged and actuated by the
push button 19 or by another insulating ele-
ment carried by the operating member 18
of the snap switch. The terminal 32 is
20 utilized for circuit connection of the motor
starting winding or the like. It is of course
to be understood that the opening and clos-
ing action of the latterly described switching
elements may be reversed or otherwise modi-
25 fied to suit the requirements of particular
installations.

By the construction and arrangement just
described upon actuation of the snap switch
operating member 18 such as to effect clo-
30 sure of the snap switch the push button 19
engages the contactor 33 and forces the latter
into engagement with the starting contact 32
thereby providing for energization of the
auxiliary starting windings of the motor,
35 the main windings being also energized
through closure of the snap switch. Follow-
ing starting and acceleration of the
motor the push button is released and there-
upon moves upwardly under the bias of the
40 spring 21 and as soon as the push button
19 frees the contactor 33 the latter moves
out of engagement with its co-operating con-
tactor 32 to thereby interrupt the circuit
through the starting winding, the snap
45 switch, however, being held in by the latch
23 in the manner aforescribed.

Said latch is provided in addition to the
features aforescribed with a laterally ex-
tending arm 35 in a position to be engaged
50 by a suitable push button or actuating ele-
ment 36 which in practice may be carried
by the housing 10 and biased as by a spring
37 out of engagement with said arm. Said
push button 36 thus provides for manual
55 tripping of the latch 23 and consequent
opening of the snap switch.

What we claim as new and desire to se-
cure by Letters Patent is:

1. The combination with a switch having
60 a part movable to opposite extreme positions
with a snap action for making and break-
ing an electric circuit, means normally bias-
ing said part to circuit breaking position,
a latch for holding the same in circuit mak-
65 ing position, and a bimetallic electro-ther-

mally responsive latch-operating member in
circuit with said part to control operation
of the latter when in circuit making position.

2. The combination with a switch having
a part movable to opposite extreme positions
70 with a snap action for making and breaking
an electric circuit, of electro-thermally re-
sponsive control means comprising a multi-
ple reflexed bimetallic strip normally in cir-
cuit with said part during circuit making
75 positioning thereof to provide for operation
of said switch automatically under given ab-
normal electrical conditions.

3. In a controller for electric motors and
the like, the combination with a switch hav-
ing a part movable to opposite extreme po-
sitions with a snap action for making and
breaking an electric circuit, of means nor-
mally biasing said part out of circuit mak-
ing position, predominant holding-in means
80 for said part, and automatically operable
means comprising a bimetallic thermostatic
strip normally in circuit with said part dur-
ing circuit making positioning thereof for
releasing said holding-in means under given
85 abnormal electrical conditions.

4. In snap switch mechanism, the combi-
nation with a contact, a co-operating con-
tactor, means for moving said contactor with
a snap action into given positions for mak-
ing or breaking an electric circuit, means for
90 normally biasing said contactor out of one
of said positions, a latch associated with
said contactor to prevent movement thereof
under said bias, and means operable auto-
matically under given abnormal electrical
95 conditions for tripping said latch, said means
comprising a multiple reflexed bimetallic
strip in circuit with said contactor.

5. In snap switch mechanism, the combi-
nation with a contact, a co-operating con-
tactor, means for effecting movement of said
contactor with a snap action to make or
break an electric circuit, means for biasing
100 said contactor out of circuit making posi-
tion, restraining means to act directly upon
said contactor for preventing movement
thereof under said bias, and a bimetallic
thermostatic member in circuit with said
105 contactor and adapted under predetermined
electrical conditions to automatically effect
release of the latter by said restraining
means.

6. In snap switch mechanism, the combi-
nation with a plurality of fixed contacts, a
110 contactor movable with a snap action into
and out of engagement with said contacts,
of means to act upon said contactor for bias-
ing the same out of engagement with said
contacts, a latch, means carried by said con-
tactor to be engaged by said latch for hold-
ing in said contactor, electro-thermally con-
trolled means for automatically disengaging
115 said latch under given electrical conditions,
said means comprising a multiple reflexed

- bimetallic strip in circuit with said contactor, and manually operable means for disengaging said latch independently of said electro-thermally controlled means.
5. 7. The combination with independently operable sets of co-operating contacts, of snap operating means providing for closure of said sets of contacts jointly, means biasing said operating means to cause disengagement of a plurality of said sets of contacts and means for holding in certain of said contacts while permitting other of said contacts to open under such bias.
10. 8. The combination with independently operable sets of co-operating contacts, of snap operating means providing for closure of said sets of contacts jointly, means biasing said operating means to cause disengagement of all of said sets of contacts, means for holding in certain of said contacts while permitting other of said contacts to open under such bias, and thermosatic releasing means for said holding-in means.
15. 9. In a controller for electric motors having starting windings to be unenergized during running, the combination with independently operable sets of contacts for the starting and running windings, of operating means for the running contacts including means to effect conjoint closure of the starting contacts, means biasing said operating means to cause opening of all of said sets of contacts, latching-in means for said running contacts and thermostatic and manual releasing means for said latching means.
20. 10. In a controller for electric motors having starting windings to be unenergized during running, the combination with independently operable sets of contacts for the starting and running windings, of snap operating means for the running contacts including means to effect conjoint closure of the starting and running contacts, means biasing said operating means to cause opening of all of said sets of contacts, latching-in means for said running contacts and ther-
- mostatic and manual releasing means for said latching means.
11. The combination with a snap make and break switch having means normally biasing the same to open position and mechanical latching-in means for the switch, of automatically operable releasing means for the switch comprising an electro-thermally responsive element of multiple reflexed form having fixed terminal portions and intermediate reflexed end portions to move jointly under electro-thermic influence for tripping said latching-in means.
16. 12. The combination with a snap make and break switch having means normally biasing the same to open position and mechanical latching-in means for the switch, of automatically operable releasing means for the switch comprising an electro-thermally responsive element of multiple reflexed form having fixed terminal and intermediate reflexed portions thereof anchored and other intermediate reflexed portions thereof movable under electro-thermic influence to exert jointly a tripping force upon said latch.
21. 13. The combination with a snap make and break switch having means normally biasing the same to open position and mechanical latching-in means for the switch, of automatically operable releasing means for the switch comprising an electro-thermally responsive element of multiple reflexed form having fixed terminal and intermediate reflexed portions thereof anchored and other intermediate reflexed portions thereof movable under electro-thermic influence to exert jointly a tripping force upon said latch, and means providing against relative movement of said reflexed portions of said electro-thermally responsive element.

In witness whereof, we have hereunto subscribed our names.

GEORGE J. MEUER.
ARTHUR H. FLEET.
